(57) **CLAIM**

We claim the ornamental design for a partition trim, as shown and described.

DESCRIPTION

FIG. 1 is a perspective view of a corner section of a partition trim embodying our design;

FIG. 2 is a side view of FIG. 1;

FIG. 3 is a front view of FIG. 1, the rear being a mirror image thereof;

FIG. 4 is a top view of FIG. 1; and

FIG. 5 is a cross section taken along the line 5—5 in FIG. 4, showing a shape of the upper surface.

FIG. 6 is a perspective view of a corner section of a second embodiment of a partition trim embodying our design;

FIG. 7 is a side view of FIG. 6;

FIG. 8 is a front view of FIG. 6, the rear being a mirror image thereof;

FIG. 9 is a top view of FIG. 6; and

FIG. 10 is a cross-section taken along the line 10—10 in FIG. 9, showing a shape of the upper surface in FIG. 6.

FIG. 11 is a perspective view of a corner section of a third embodiment of a partition trim embodying our design;

FIG. 12 is a side view of FIG. 11;

FIG. 13 is a front view of FIG. 11, the rear being a mirror image thereof;

FIG. 14 is a top view of FIG. 11; and,

FIG. 15 is a cross section taken along the line 15—15 in FIG. 14, showing a shape of the upper surface.

The dashed lines and cross sections lines in FIGS. 1—15 are to show the environment and do not form a part of the present invention.

The claimed design is broken on the ends to indicate indefinite length.
